ATTORNEY.

UNITED STATES PATENT OFFICE.

ANDREW JACKSON LUTHER, OF BURNS, TENNESSEE.

TOBACCO-ELEVATOR.

SPECIFICATION forming part of Letters Patent No. 576,735, dated February 9, 1897.

Application filed May 15, 1896, Serial No. 591,600. (No model.)

To all whom it may concern:

Be it known that I, ANDREW JACKSON LUTHER, a citizen of the United States, residing at Burns, in the county of Dickson and State of Tennessee, have invented certain new and useful Improvements in Tobacco-Elevators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to hoist tobacco up to the place where it is hung in a barn with greater facility and at less expense than is now the case, so that the work may be readily done by the farmer and a boy, 20 while now it requires three or four men for the same thing.

Figure 1 of the drawings is a perspective view; Fig. 2, a side elevation showing the lever and parts connected therewith; Fig. 3, 25 a detail view of the tobacco-holder on the traveling pulley-frame. Fig. 4 is a vertical section to illustrate the arrangement of the hoisting-rope.

In the drawings, A represents a barn-floor, 30 to which is detachably secured a block B, provided with the staples b b on top. To each of these staples I attach the lower end of a cord or rope C, whose upper end is fastened to the lower end of a plate D. This plate has 35 the longitudinal slot d and the vertical row of holes d', the latter being intended to receive a detachable stop-pin d².

E is a horizontal board in the upper part of barn, the same being provided with the slots 40 e e, through which the plates D are movable, so as to make the ropes C C taut before the hoisting begins.

45 F are levers fulcrumed on and in grooves of the upright G and having two prongs at the front end, so as to straddle the plates D. The prongs rest on the board E and support the stop-pins d², as shown in the drawings, in whatever holes d' they may be placed. Between the slots e e the board E has an open-

ing e', in which is pivoted the frame G' on a 50 cross-pin e². This frame carries two vertically-alined pulleys H, while a similar frame K below it also carries two similar pulleys in vertical alinement, but the latter also carries the tobacco-holder L as it is moved up and 55 down. The holder L has pairs of arms l', from one to four pairs, whose ends are turned up to prevent the sticks on which the split tobacco-plants are hung from slipping off. It also has holes ll, through which pass the guide- 60 ropes C C.

l² are rods by which the holder L is attached to the frame K.

M is a pulley rope or cord secured at one end to a cross-bar m or other convenient fixture in the upper part of barn, and thence carried over the top pulley of frame G', then down under the bottom pulley of frame K, then up over the lower pulley of frame G', then down under the upper pulley of the 70 frame K, and finally up to the lower end of frame G', where it is made fast. A boy of twelve to fourteen years of age after loading up the holder with the sticks of tobacco by 75 simply pulling on the rope M can hoist them up to a man in the upper part of the barn, so that he can conveniently arrange them in place.

Having thus described all that is necessary to a full understanding of my invention, what 80 I claim as new, and desire to protect by Letters Patent, is—

The combination with the stationary bottom block B, of the guide-ropes C C having their lower ends secured to said bottom block 85 B, the plates D each of which has a vertical series of holes, the pins d² adapted to fit in said holes, the levers F adapted to engage said pins, and a vertically-movable tobacco-holder L adapted to be guided in its movements by the ropes C substantially as described.

In testimony whereof I affix my signature in presence of two witnesses.

ANDREW JACKSON LUTHER.
